UNITED STATES PATENT OFFICE.

LACHLAN MACLEAN BEATSON, OF ASHTON, KANSAS.

HAT-FASTENER.

1,082,789.

Specification of Letters Patent.

Patented Dec. 30, 1913.

Application filed November 27, 1911, Serial No. 662,604. Renewed October 13, 1913. Serial No. 795,010.

To all whom it may concern:

Be it known that I, LACHLAN MACLEAN BEATSON, a citizen of the United States, residing at Ashton, in the county of Sumner 5 and State of Kansas, have invented certain new and useful Improvements in Hat-Fasteners, of which the following is a specification, reference being had to the accompanying drawings.

10 This invention is an improved hat fastener especially designed for fastening ladies' hats in position on the head and arranged to permit the wearer to place the hat in proper position and to fasten it securely and to yet 15 allow the hat to be readily removed when desired, the invention consisting in the construction, combination and arrangement of devices hereinafter described and claimed.

In the accompanying drawings: Figure 1 20 is a sectional view showing two of my improved hat fasteners in applied position, a hat being shown in dotted lines. Fig. 2 is a detail sectional view on a larger scale of one 25 of the hat fasteners; Fig. 3 illustrates in perspective the different parts detached.

My improved hat fastener comprises a socket member 1 for attachment to a hat and a pin 2 for engagement with the hair. In practice, two of the fasteners will be used 30 with a hat and the members 1 will be secured in the hat as by stitching, usually directly opposite each other. The socket member 1 comprises a plate 3 which is formed with an inwardly extending tongue 4 struck up 35 therefrom and also with openings 5 which are arranged on three sides of a quadrangle. Combined with the plate 3 to form the socket member 1 with its downwardly facing opening and its opposed inner and outer spaced 40 walls, is a casing 6 which is preferably struck up from a single piece of material, usually sheet metal, being formed on its walls 7 with tongues 8 which are passed through the openings 5 and clenched on the 45 reverse side of the plate 3, as best illustrated in Fig. 2. The casing 6 incloses the inwardly extending tongue 4 and together with the plate 3, forms a socket 9 which is open below.

50 The pin member 2 is, in effect, a hairpin of suitable size and is preferably made of tortoise shell, either real or imitation, but may be made of any suitable material and may be provided with any desired number of 55 tines 10. The tines of the pin member are curved longitudinally so that the said mem-

ber may be engaged with the hair on the head of the wearer and pushed up into the same, said tines curving upwardly and inwardly from their shank toward the upper central portion of the head crown. The shank 11 of the pin member 2 is at the lower end thereof and is of Z shape, as clearly illustrated in Figs. 2 and 3 embodying extreme elements connected together by an 60 oblique intermediate element 13 to form a clasp 12, the outer extreme element 14 of the shank terminating at its lower end in a finger piece 15 and being formed with an opening 16 to receive the tongue 4 when the shank is forced up into the socket 9. The parallel extreme elements of the shank occupy the same relation to each other as do the walls of the socket member. One side of the opening 16 forms a shoulder which 65 co-acts with the inwardly extending tongue 4 so as to cause the shank to detachably lock the lower end or head of the pin to the socket member 1.

By pressing inwardly on the finger piece 70 15, which is adapted to lie outside of the socket member, the extreme element 14 may be disengaged from the tongue 4 and the shank may be then withdrawn from the socket 9 so as to permit the pin to be entirely detached from the socket member and hence admit of the removal of the hat, while 75 leaving the pins in the hair. In practice, the pins will be ornamental and will serve as side-combs when the hat is removed as well 80 85 as operating to co-act with the hat or socket members to secure the hat in position on the head.

While I have herein shown and described 90 a hat fastener which embodies all the features of my invention I would have it understood that changes may be made in the form, proportion and construction of the several parts within the scope of my invention as defined by the appended claims. I would also 95 have it understood that the various portions of the hat fastener may be made of any suitable material and may be either plain or ornamental, as may be desired.

Having thus described my invention I 100 105 claim:

1. A hat fastener comprising a socket member adapted to be secured to the hat, said member being open below and having opposed inner and outer spaced walls, one of 110 the walls having an inwardly extending tongue, in combination with a pin member

having a Z-shaped shank of which the extreme elements occupy the same relation to each other as do the walls of the socket member, one of the extreme elements being provided with an opening to receive the tongue and together with the diagonal element arranged to spring into the socket member with the opening in register with the tongue, while the other one of the extreme elements is adapted to lie snugly on the exterior face of the other socket wall and maintain the first extreme element in engagement with the wall of the socket member, the pin being curved upwardly and inwardly from its shank.

2. A hat fastener comprising a socket member adapted to be secured to the hat, said member being open below and having vertical inner and outer spaced parallel walls, the outer one of the walls having a tongue struck inwardly therefrom, in combination

with a pin member having a Z-shaped shank of which that one of the parallel elements remote from the pin point is provided with an opening to receive the tongue and together with the diagonal element is arranged to spring into the socket member with the opening in registry with the tongue, while the other one of the parallel elements is adapted to lie snugly on the exterior face of the inner socket wall and maintain the first parallel element in engagement with the wall of the socket member, and a finger piece on the exterior of the parallel element and adapted to lie outside the socket member, the pin being curved upwardly and inwardly.

In testimony whereof I hereunto affix my signature in the presence of two witnesses.

LACHLAN MACLEAN BEATSON.
